UNITED STATES PATENT OFFICE.

GLENN W. PACKER, OF CHICAGO, ILLINOIS, ASSIGNOR TO GOODMAN MANUFACTURING COMPANY, OF CHICAGO, ILLINOIS, A CORPORATION OF ILLINOIS.

SCRAPER.

Application filed April 16, 1923, Serial No. 632,233. Renewed September 29, 1925.

To all whom it may concern:

Be it known that I, GLENN W. PACKER, a citizen of the United States, residing at Chicago, in the county of Cook and State of Illinois, have invented new and useful Improvements in Scrapers, of which the following is a specification.

This invention relates to improvements in scrapers used for transporting loose material and more particularly to scrapers adapted to have reciprocal movement toward and away from the material to be transported.

In my prior application bearing Serial Number 470,771, filed May 19, 1921, and allowed on February 2, 1923, a scraper of the class above described is shown in which the scraper comprises a body portion having two rear closure members hinged on opposite side walls thereof, these hinged members being operatively connected both with the head rope and with the tail rope so as to be swung laterally into open position when the scraper is moved rearwardly, and closed when the scraper is moved forwardly. In the specific form disclosed in the prior application, the operative connection between the head rope and the two hinged rear wall portions comprises a pair of flexible terminals, each of which is connected at its rear end to a cross arm on the scraper body, then passes rearwardly about a pulley carried on a closure member, and thence forwardly about a guide on the same side wall to which the closure member is hinged.

In the present improved form disclosed in the present application, each of the head rope terminals is connected directly to a closure member and extends forwardly across the other terminal and about a guide on the opposite side wall, whereby the construction is simplified and more positive operation is afforded. Other improved features of construction will appear from the following detailed description.

My invention may best be understood by reference to the accompanying drawings in which:

Figure 1 is a plan view of the scraper constructed in accordance with my invention,

showing the rear wall portions in closed position in full lines and in open position in dotted lines.

Figure 2 is a transverse section of the scraper showing one of the rear end wall portions in open position.

Referring now to the details of the embodiment of my invention illustrated, the scraper is adapted to be moved by flexible draft ropes comprising a head rope 10 and a tail rope 11 for moving the scraper forwardly and rearwardly respectively. The apparatus is set up in the usual manner with the draft ropes trained over fixed guides or sheaves and operatively connected with any suitable power device, such as a hoisting engine. The scraper comprises a body portion 12 having side walls 13^a, 13^b, connected by front and rear cross members 14 and 15 respectively. The drawings illustrate a preferred form of scraper having no bottom but a bottom may be provided without departing from the scope of my invention. The lower margins of the side walls are inclined or turned inwardly to form substantially horizontal cutting edges 16, 16 as shown. The rear end of the scraper comprises two upright closure members 17^a, and 17^b, which may be similar in construction and each pivotally connected to the rear end of the side walls 13^a, 13^b respectively, as indicated at 18, 18. The bottom margins of the closure members are preferably inclined or turned inwardly so as to form cutting edges 21, 21, similar to the cutting edges 16, 16 of the side walls. The arrangement is such that the closure members normally form a closure for the rear end of the scraper and are mounted to swing laterally and rearwardly into a position substantially parallel with each other, or into substantial alignment with the adjacent side walls of the scraper.

Means coacting with the draft ropes are provided for actuating the closure members so as to open the rear end of the scraper when it is being moved rearwardly and close the rear end when it is moved forwardly. This is accomplished by operatively connecting both head rope 10 and tail rope 11

to the pivoted closure members 17^a and 17^b so as to tend to swing them in opposite directions depending upon the relative tension on the two draft devices. In the present invention the head rope connection comprises a pair of flexible terminals 23^a, 23^b connected respectively at the rear ends to brackets 24^b and 24^a, projecting inwardly from the closure members 17^b and 17^a respectively. From their point of connection with the closure members the terminals extend forwardly in crossed relation with each other, the terminal 23^a passing about a sheave or guide 25^a adjacent the forward end of the side wall 13^a while the other terminal 23^b passes about a similar sheave or guide 25^b on the side wall 13^b. These terminals 23^a and 23^b may be connected to the head rope 10 in any suitable manner as for instance in the form shown they are integral and continuous, passing freely about a pulley 26 connected with the head rope 10.

The tail rope 11 extends between the ends of the wall portions 17^a and 17^b and is provided with a pair of terminals 30, 30 connected to arms 31, 31 extending inwardly from said wall portions. These arms are preferably arranged adjacent the respective pivoted ends of the closures so that when the latter are in closed position, as shown in full lines in Figure 1, said arms project substantially at right angles to their respective connecting terminals 30, 30, thus affording a maximum leverage for opening the closures when the scraper is moved rearwardly by the tail rope, and also tending to maintain the door in open position while digging or gathering a load. It will be further noted that the arms 31, 31 are arranged to form stops to limit the inward movement of the closure members 17^a and 17^b, as for instance, said arms engage the downwardly extending portions 15^a, 15^b of the cross bar 15 when their respective closures are closed, as shown in Figure 1. Means are also provided for limiting the outward pivotal movement of the wall portions, for example, a pair of chains 35, 35 may be connected between the cross bar 15 and the respective closure members.

The operation of the scraper above described is as follows:

The apparatus is set up in the usual manner for reciprocable movement between a pile of loose material and an unloading or discharge point. The tail rope 11 is trained over the pile and when tension is placed thereon the scraper is moved rearwardly with the closure members 17^a, 17^b standing open in substantially parallel relation with each other so as to offer a minimum resistance as the scraper cuts into the material at the toe of the pile. When the scraper has been advanced sufficiently to gather a load the pull on the tail rope 11 is discontinued

and tension is placed on the head rope 10. Owing to the connection of the head rope terminals 23^a and 23^b to the wall portions 17^b and 17^a, respectively, a pull on the head rope tends to pivot the closure members inwardly and close the rear end of the scraper, whereby the material in the scraper will be enclosed and moved forwardly.

In the preferred construction forming the subject matter of the present invention it will be seen that the crossed arrangement of the head rope terminals 23^a and 23^b intermediate the guides 25^a and 25^b and the closure members to which they are respectively connected, affords a construction in which the leverage tending to close the closure members is sufficient to operate the latter without the use of pulleys or the like, that is to say, the terminals are directly connected to the closure members instead of passing around pulleys as was proposed in my prior application referred to. The arrangement forming the subject matter of the present invention therefore has the advantages of simplicity in construction and quick and positive operation, which have been shown to be desirable in a scraper of this character.

The arrangement of the arms 31, 31 to which the tail rope terminals 30, 30 are connected is also such as to provide maximum leverage in opening and maintaining the closure members in open position when tension is placed on the tail rope. These arms also form convenient stops to limit the inward movement of the closures.

Although I have shown and described one form in which my invention may be embodied, it will be understood that the construction and arrangement of the parts may be varied without departing from the spirit and scope of my invention. I do not therefore wish to be understood as limiting myself to the specific construction illustrated herein excepting as specifically limited in the appended claims.

I claim as my invention:

1. A scraper having connected side walls, two members normally forming a closure movably mounted to extend rearwardly in open position, and two draft devices having operative connection with said closure members and tending to move them in opposite directions, one of said draft devices having two terminals each extending about laterally spaced guides on the scraper and thence in crossed relation with the other to operative engagement with the closure member on the opposite side of the scraper.

2. A scraper having connected side walls, two closure members each pivotally connected with one of the side walls to open laterally, two flexible draft devices for reciprocably moving said scraper operatively connected with said pivoted closure members and tending to move them in opposite

- directions, one of said draft devices having two terminals each extending about a spaced guide mounted on one side wall, and thence in crossed relation with the other 5 terminal to operative engagement with the closure member hinged to the opposite side wall.
3. A scraper having connected side walls, two members normally forming a closure 10 movably mounted to extend rearwardly in open position, and two draft devices having operative connection with said closure members and tending to move them in opposite directions, one of said draft devices having 15 two terminals each extending about laterally spaced guides on the scraper thence and in crossed relation with the other to direct engagement with the closure member on the opposite side of the scraper.
- 20 4. A scraper having connected side walls, two closure members each pivotally connected with one of the side walls to open laterally, each of said members having a projecting arm adjacent the pivoted connections thereof, said arm extending forwardly along 25 its adjacent side wall in closed position of the members and forming a stop to limit the inward movement of said members, two flexible draft devices for reciprocably moving said scraper operatively connected with said pivoted closure members and tending to move them in opposite directions, one of said draft devices having a pair of terminals directly connected to said inwardly projecting arms.
5. A scraper having connected side walls, two closure members each pivotally connected with one of the side walls to open laterally, each of said members having a projecting arm adjacent the pivoted connections thereof, said arm extending forwardly along 30 its adjacent side wall in closed position of the members and forming a stop to limit the inward movement of said members, two flexible draft devices for reciprocably moving said scraper operatively connected with said pivoted closure members and tending to move them in opposite directions, one of said draft devices having a pair of terminals directly connected to said inwardly projecting arms. 35

Signed at Chicago, in the county of Cook 50
and State of Illinois, this 3rd day of April,
1923.

GLENN W. PACKER.
